CIRCUIT SYSTEM FOR ELECTRONIC MEMORY TUBES

Walter Emil Wilhelm Jacob, Hagersten, Sweden, assignor to Telefonaktiebolaget L M Ericsson, Stockholm, Sweden, a corporation of Sweden

Application February 25, 1954, Serial No. 412,599

Claims priority, application Sweden February 27, 1953

1 Claims. (Cl. 315—12)

The present invention is a circuit system for storing information in electronic memory tubes. The storing process in question is so arranged that the storage elements in such a tube are given a marking in the form of a stable potential, in general either one of two values, whereby the marking can be regarded as expressing a binary function.

A tube, as used in the invention, contains at least one electron emitting cathode, arrangements for controlling the current which is emitted from the cathode, a number of secondary emission electrodes functioning as storage elements, which electrodes, connected by means of outer impedances, can assume two different stable potentials on account of their negative resistance characteristic within a certain voltage range, a collector electrode for collecting the primary current or the secondary emission currents and the secondary collector currents. All the storage elements are, in a tube of this type, electrically directly accessible from the outside of the tube.

The invention for storing information in such a tube, is in principle characterized by the fact that a marking potential is applied to the respective storage element through its outer impedance, which potential may have two different values, and that at the same time or before switching on the primary electron current of the valve, the cathode is brought to a certain potential, differing from the normal condition, for example in that a pulse is applied.

The invention will hereinafter be described with reference to the drawing:

Fig. 1 a schematic diagram showing a tube according to the invention.

Fig. 2 voltage current characteristic for a storage element of the type shown in Figure 1.

Fig. 3 shows a circuit for connection of a storage tube.

Fig. 4 shows a current voltage characteristic of an element as used in a circuit shown in Fig. 3.

Fig. 5 shows a circuit arrangement using a double gas discharge triode.

Fig. 6 is a diagram showing the grid and cathode potentials in the circuit shown in Fig. 5.

The method of operation of a storage tube according to the invention will first be described.

A tube of this type contains a hot cathode as an electron emitting source, a control grid, which usually operates with a negative bias potential, a positively charged accelerating electrode, a collector electrode, and several storage elements. Fig. 1 shows a schematic view of the tube. An electron current starts from the cathode k and is controlled by the control grid g_1 , the electrons being accelerated by the accelerating electrode g_2 , whereupon they impinge partly on the collector electrode g_3 and partly on the storage elements e . As long as these elements are maintained at cathode potential the electrons are unable to reach them, but as soon as one of these elements receives a positive potential an electron current will start towards this element, which current

2

will initially increase with the applied potential. Due to the starting of secondary emission this current will not increase as a linear function of the potential but will pass through a maximum and then decrease. At a certain potential where the secondary emission factor of the element is equal to 1, the current will again decrease to 0, and will become negative at values above this potential. After the current has passed a minimum on having the potential increased further, it will once again pass through the 0 point at a potential, which is about the same as that of the collector electrode.

Fig. 2 shows the characteristic of such an element, which is negative within a certain range. If such an element is connected to a sufficiently high positive potential V_0 via a large resistance R_a , which is so large that the resistance line for R_a intersects the element characteristic in three points S_1 , S_2 and S_3 , it will be obvious from the known conditions of stability that only the intercepts S_1 and S_3 are stable, while S_2 is an unstable equilibrium position. In such an arrangement it is, therefore, possible for an element to remain at only two stable positions, either a higher position and higher value for the point S_3 in the neighbourhood of the collector electrode potential, or a lower value, corresponding to S_1 near the cathode potential. Hence, if a "mark" is produced on a number of elements or a single element, with a potential corresponding either to the higher or the lower limit, the tube will store information of a binary nature. As a consequence the expressions "positively marked" or "negatively marked" element, imply that the elements after a marking procedure will be locked to the potentials S_3 or S_1 respectively which are, as described above, the higher and lower stable potentials respectively.

This invention is concerned with a novel system for applying these markings. In order to clarify this system some of the known systems will now be related. A positive marking is for example most easily obtained by increasing the outer positive marking potential V_0 applied externally through the resistance R_a (see Fig. 2) to such an extent that the points S_1 and S_2 coincide or in fact might not appear. S_1 will then also be unstable and the element potential increases instantaneously to the higher stable value. In order to mark the element negatively, the opposite arrangement should be adopted, in other words, the application of such a large negative marking potential that the intersection S_3 will be the tangential contact point of the element characteristic within the area for its minimum or does not appear at all.

Such simple arrangement, however, fails when it is a question of a number of storage tubes which are so connected that they might be manipulated from a common marking arrangement. Such a connection is shown in Fig. 3. In the case of a number of storage tubes m the elements marked with the same number n , connected over the individual resistances R_{a1} , R_{a2} . . . R_{an} are connected to common marking voltage sources V_{01} , V_{02} . . . V_{0n} . The marking procedure already mentioned would in all tubes give the same marking which is naturally not desirable. If the marking process is to be accomplished in only one of these m tubes, this is only possible through another arrangement in connection with an additional local switching function applied to this tube. In such arrangement the marking potentials V_0 are only limited in such a way that there are always three points of intersection with the element characteristic. For a positive marking the potential V_0 lies above the unstable positions of equilibrium S_2 , and for a negative marking ($V_0=0$) below S_2 . In order to accommodate S_2 . Fig. 2 shows an example with two given potentials of V_0 for positive marking above S_2 , and V'_0 for nega-

tive marking ($V_0=0$) below S_2' . In order to accomplish the storage of the information in a certain tube, which corresponds to the applied marking potentials, the primary electron current is suppressed for a moment in this tube. The elements leave thereafter their respective stable potentials and the marking potentials V_0 respectively V_0' are applied externally. After the tube current has started again the element potentials, corresponding to their position above or below the point of unstable equilibrium S_2 , S_2' respectively, are instantaneously 10 locked in their new stable potentials and remain there for some time, positively or negatively marked, even after the suppression or alteration of the marking potentials.

Such arrangement has however many disadvantages. For example it is not possible to mark two different tubes simultaneously when using opposite marking processes. Further, it is not possible to mark a number of elements positively in one tube and to mark simultaneously in one or more other tubes all the elements negatively, a case which in practice is very common, if a negative marking of all elements in one tube is synonymous with an erasure of the information stored therein. The reverse case is, of course, also possible.

Another disadvantage of this arrangement is that limited tolerances within the element characteristics must be maintained. For example, it may happen that for a certain tube the positive marking potential V_0 for a certain element n still is not sufficiently high, i.e. so that V_0 barely lies above S_2 , while the same potential for the same element of another tube is too high, for example so that S_1 and S_2 coincide or that no points of intersection S_1 or S_2 exist.

In this case the element in this tube would instantly get the positively marked condition. This difficulty is particularly pronounced in a special method of reading, which case will be described shortly below.

Generally speaking the methods of reading are based on the fact that the inner resistance between the collector electrode and the positively marked elements is low and that thereby, by means of a modulation of the collector potential, an output signal can be obtained in the different element circuits, while if the inner resistance between the collector and the negatively marked elements is high, a modulation of the collector potential has no influence on the elements. Fig. 3 shows a reading arrangement, by means of which the collector potential is held constant and the tube current is modulated by pulses. The tubes are then usually non-conducting and are pulsed periodical- 50 ly in a certain sequence by a multiplex system, so that one tube at a time is rendered conductive during its pulse time. The corresponding elements n are interconnected by means of condensers C_n with common output resistances $R_{a'n}$. The potentials of the elements are no longer fixed in this circuit. A positively marked element tends to shift from its potential in the pulse pauses. By choosing a suitable time constant $C_n \times R_{a'n}$ in relation to the pulse frequency it is assumed, that the element shifts from its potential only to an extent such, that during the pulse time the original potential can be regained. The re-charging of the condensers C_n causes potential alterations of the pertinent output resistances $R_{a'n}$, which alterations are used as an output signal.

A negative marked element tends during the pulse pauses to have the marking potentials applied externally. This is, however, not desirable, unless the potential displacements of the negatively marked elements also are to be used as output signal, which in this case would have the opposite sign as opposed to that obtained from the positively marked elements. There is a danger, however, that the potential of such an element during the pulse interval obtains a value, which lies above the unstable point of equilibrium S_2 (see Fig. 2) and that thereby the elements during the following pulses instantly move to the positively marked condition. The relatively small positive

5 current maxima of the element characteristics and the relatively small distance between the points S_1 and S_2 favour this tendency. If one also must consider the spread of the characteristics, it is evident from above, that a correct design of such a circuit is almost impossible.

6 The disadvantages mentioned above are avoided by this invention as will be described in the following. The invention provides that for both marking processes two different manipulations are used so that it is possible to perform in a circuit according to Fig. 3, for example, simultaneously in one tube a positive marking of separate elements and in one or more other tubes a negative marking of all elements. Further combinations are possible but need not be described separately.

7 The circuit system of the invention is further characterized by the fact that the marking potentials are placed in the negative area $V_0 \leq 0$ volt with reference to the normal cathode potential. Thereby, the negatively marked potentials always lie on a potential where they carry no current and in accordance therewith this potential does not change, whether the tube is conductive or not. For bringing the elements, which have now a permanent fixed potential for marking purposes, to a point above or below the unstable equilibrium point of their characteristics, the cathode potential is shifted while the tube is blocked, in such a manner that, when the tube is conductive again, a different characteristic appears, which is shifted with respect to the original characteristic, and thus the conditions for a marking process are fulfilled in accordance with what is already known.

8 Further in order to clarify the function, an example with reference to Figs. 3 and 4 will be described below. On the elements $1-n$ of all tubes the marking potentials V_0 and V_0' have arbitrarily been applied which marking potentials differ from each other by a certain constant value. V_0 will for example be 0 volt and V_0' will have a negative value with reference to cathode potential. If now in a certain tube m a mark process is to be performed in order to mark the elements, corresponding to the applied potentials V_0 or V_0' respectively, positively or negatively, respectively, the cathode potential is displaced, after the suppression of the tube current, so far into the negative area that after the current flow or current pulses, respectively have started again, a characteristic will appear with an appearance approximately of the same type as shown in Fig. 4 (dashed line), whereby in relation to this the elements, which are marked with the marking potential V_0 will lie above the unstable point of equilibrium (respectively above the positive maximum of the characteristic—because this method works also if there is no point of intersection in the first positive current area) and thereby suddenly increase to the positively marked condition corresponding to the point of intersection S_3 . The elements supplied with a negative potential are not influenced if they have not before been positively marked, because their potential then suddenly decreases from S_3' to V_0' when the tube current is suppressed. After the marking process the cathode potential may naturally return to its normal value.

9 A negative marking of all elements in a tube is successful in this arrangement if the tube current is suppressed for a short time, irrespective of which of the two marking potentials V_0 and V_0' is applied to the elements in this case. For this reason it is possible to apply marking processes of different nature in several tubes simultaneously.

10 One may generalize these conditions if one from the beginning assumes two marking potentials with different values and displaces the cathode potential with reference hereto, so that depending on the requirements the corresponding elements are locked by the displacement of the cathode potential and are marked in one or other sense. If one makes the negative displacement so large that also the elements with the externally applied lower

potential V'_0 are included for a positive marking it is possible to apply simultaneously three marking processes differing from each other in different tubes with the same externally applied marking potentials, namely: (1) positive marking of a certain number of elements in one tube (2) positive marking of all elements in one or several other tubes (3) negative marking of all elements in one or several other tubes. In a similar way it is also possible to change the conditions by means of positive marking potentials which will cause similar effects with cathode displacements in a positive sense.

In actual practice positive markings are produced by means of negative cathode pulses and negative markings by means of current suppression. Fig. 5 shows an example wherein the switching function is carried out by means of a double triode of the gas filled type. This double triode consists of a common anode a , two cathodes k_1 and k_2 and two trigger electrodes t_1 and t_2 . The double tube with its common anode resistance R_1 for both discharge gaps as also the cathode resistances R_2 and R_3 are so connected that only one half, in other words either the discharge gap at_1k_1 or the gap at_2k_2 will glow at the same time. Due to the fact that the trigger electrodes t_1 and t_2 are supplied with suitable striking potentials it is possible to transfer the glow discharge from one half to the other. For every changeover a charging current will flow to the condensers C_1 and C_2 respectively which will cause a larger fall of potential to appear across R_1 . The negative potential pulse is transmitted through condenser C_3 to the control grid g_1 of the storage tube. The grid of this tube has normally such a negative bias across the resistance R_4 taken from a bias potential that current can flow only during the positive portions of the pulses P supplied by the pulse transformer P . If a negative impulse is now applied from the gas discharge triode the grid potential will be displaced so far into the negative area that the storage tube will be completely blocked. The time of duration of this blocking is determined usually by the time constants which are formed by R_1 , C_1 and R_1C_2 , respectively. A negative marking in the storage tube is obtained by the ignition of the glow discharge triode at_1k_1 controlled by the time constant R_1C_1 . It is natural that the time constant must be chosen in such a way that the time will be sufficient for the positively marked elements to discharge in the lower stable potential areas. In order to perform a positive marking process the discharge is shifted to the discharge gap at_2k_2 during which period the grid in the storage tube will receive a negative potential pulse due to a charging current for C_2 . Simultaneously a charging current transient is transferred through the primary winding of a transformer T . The secondary winding of this transformer constitutes, together with the condenser C_4 a resonant circuit, which by means of the current transient in the primary winding will initiate a damped oscillation. The polarity of the transformer circuit has been chosen in such a way that the first half cycle of the oscillation is negative. Only the first negative half cycle can be transmitted to the cathode of the storage tube. The oscillation is suppressed after the first half cycle by means of the short circuiting diode D_3 . The design of the circuit

has been chosen in such a way that the current in the storage tube starts exactly when the cathode pulse passes its negative maximum. A diode combination D_1D_2 is used in order to ensure that the grid cathode bias never exceeds the potential of the bias source, i.e. as soon as the negative grid impulse and the negative cathode impulse differ from one another by an amount corresponding to the grid bias, the diode D_1 closes and the grid bias is then taken over by means of the diode D_2 , which becomes conducting at the same instant, by the condenser C_5 and the cathode, in such a way that the grid impulse will be transmitted in parallel to the cathode impulse, which means that the storage tube will remain in the cut-off state even during the intervals between the pulses applied to the grid by the pulse transformer.

Fig. 6 shows graphically the function of the potential of the grids and the cathodes for both manipulations. If, for example, at the time T a negative marking process is made, the negative grid potential will instantaneously be strongly negative and will go along curve 1 back to the $-V_{g1}$ -line. For a positive marking process the same thing happens in the grid circuit only with the exception that the grid potential goes back faster to the starting point, approximately in accordance with curve 2. 2. Simultaneously the cathode pulse with the zero-line as a base appears (see curve 3). Because of the diode connection D_1D_2 the grid pulse at the point where its difference, compared with the cathode pulse, is the same as V_{g1} , deviates from curve 2 and runs in parallel to the cathode pulse corresponding to line 4 back to the $-V_{g1}$ -line.

As the embodiment above described for the performance of marking processes only is an example of the circuit, which is suitable for certain purposes, the invention is not limited to this circuit.

I claim:

A circuit system for storing information by marking an electronic storage tube having at least one electron emitting cathode, means for control of the electrons emitted from the cathode, several secondary emission electrodes constituting storage elements, said electrodes being interconnected with outer impedances and arranged to obtain two different stable potentials within a certain potential range due to their negative current voltage characteristic and a collector electrode for collecting the primary and the secondary electron currents, all said storage elements being separately and directly electrically accessible from the outside of the tubes, said system comprising means for applying a marking potential to the respective storage element through the respective outer impedance, said marking potential differing from the normal operating potential of the cathode, and means for discharging the primary electrons into the direction of all the storage elements simultaneously.
